DETACHABLE HOT WATER UNIT FOR FAUCETS

Filed Sept. 6, 1930

INVENTOR:

SAMUEL S. TORRISI,
BY
William J. Jackson
ATTORNEY

UNITED STATES PATENT OFFICE

SAMUEL S. TORRISI, OF PHILADELPHIA, PENNSYLVANIA

DETACHABLE HOT WATER UNIT FOR FAUCETS

Application filed September 6, 1930. Serial No. 480,046.

This invention, stated in its broadest terms, relates to a water heater and has more especial relation to that type of device which is electrically heated.

The leading object of the present invention may be said to reside in the providing of a device which is self-contained, portable, and arranged for ready, detachable connection as a unit to the cold water faucet of conventional plumbing.

A further object of the present invention is to provide a unit to include novel devices for automatically operating an electric switch whereby a circuit through resistance coils of the heater may be made by the flow of cold water through the device.

A still further object of the present invention is to provide a device of the character stated in which the opening or closing of a faucet to which the device is detachably connected operates to make or break the circuit through the resistance coils of the heating element.

A still further object of the present invention is to provide a two-part casing of bakelite or equivalent material which may be moved to desired configuration to provide a strong, durable, light, and comparatively inexpensive structure.

A still further object of the present invention is to provide a device of the character stated in which is employed a floating valve operable by the circulation of running cold water to close an electric circuit through the resistance coils of the heating element.

A still further object of the present invention is to provide a device of the character stated in which the supply of electric current to the resistance coils of the heater is controlled manually in addition to the automatic switch which is controlled by the stoppage of running water.

A still further object of the present invention is to provide a device of the character stated in which electric current to the resistance coils of the heating element is supplied through a wall plug and socket.

A still further object of the present invention is to provide a device of the character stated in which a casing of molded insulat-

ing material is provided with a detachable cap for supporting the heating element including its resistance coils.

With these and other objects in view, the invention consists of the novel construction hereinafter described and finally claimed.

The nature, characteristic features and scope of the invention will be more fully understood from the following description taken in connection with the accompanying drawings forming part hereof, and in which:

Fig. 1 is a view in side elevation of a hot water unit embodying the invention and showing the same in application to a faucet;

Fig. 2 is a view in central section of the unit shown in Fig. 1; and

Fig. 3 is a top or plan view of Fig. 2.

Referring now to the drawings in detail, the reference numeral 10 designates a casing of molded insulating material, preferably of bakelite. The casing 10 is provided with a horizontal extension 11 terminating in a vertical stem 12 having a generally flared mouth 13 provided with a seat upon which is fitted a washer or gasket 14, preferably of some pliable material as rubber. The flaring mouth 13 is interiorly screw threaded to receive a mouth piece 15, which mouth piece in practice is screwed down upon the washer or gasket 14. The casing 10 also has extended therefrom a horizontally arranged extension 16 provided with a spout 17. Interiorly the casing 10 is provided with a chamber 18 which is in communication with the extensions 12 and 16, as clearly shown in Fig. 2.

In practice these extensions at the time of molding of the casings are provided with passages, and in order to withdraw the core during a molding process it is necessary to employ core openings, and in order to cover these core openings when the device is completed, use is made of core plugs 19. The passage in the extension 11 is provided with a floating valve 20 having therein a passage 21 terminating in an open port. This floating valve is so arranged that as water flows through the passage in the valve this open port 22 is caused to register with the chamber 18 and permit the flow of water into the chamber 18. The floating valve is provided

with a stop 23 to prevent undue rearward movement of the valve. The forward end of the valve is provided with a pin 24 which is adapted to abut against the free end of the leaf spring 25 which is secured as at 26 to the inside of casing 10. The spring 25 is provided with a contact point 26 which in the forward movement of the floating valve is adapted to contact with a contact point 27 carried by leaf spring 28, which is fixed as at 29 to the bottom of the casing 10. The casing 10 at its upper part is interiorly screw threaded to detachably receive a head 30 passing vertically through which are elongated screws 31 and 34 secured with respect to said head by lock nuts 32. Arranged within the chamber 18 are resistance coils 33 electrically connected with respect to screw 31 and to the spring 28. Electrically connecting screw 34 with spring 25 is a lead 35.

Fitted to the head 30 are upwardly projecting screws 36. Seated upon head 30 is a disc 37 which is held in position by the screws 36. This disc 37 is provided with contact pieces 38 and 39, of which contact 38 is connected to screw 31 and contact 39 is connected to screw 34. Connecting the contacts 38 and 39 are conductors 40 and 41 which are in electrical connection with plug 42 adapted for connection with socket 43, see Fig. 1. The conductors 40 and 41 lead into a cap 44 seated upon disc 37 and are in electrical connection with any conventional form of switch operable by means of a knob 45.

A description will now be given of the manner of using the above described novel device for heating water from a faucet 46 as shown in Fig. 1. That end of the device which is provided with the rubber washer 14 is fitted over the spout of a faucet 46 and the plug 42 caused to engage socket 43. With the turning on of the faucet 46 a stream of cool water passes through the passage in extension 12 and causes the floating valve 20 to move to the left in Fig. 2, thereby causing the contact points 26 and 27 to form an electrical connection for the passage of current through the resistance coils 33, it being understood that electrical current is passing through conductor 40, contact strip 38, screw 31, resistance coil 33 to spring 28, contact points 26 and 27, spring 25, conductor 35, screw 32, contact strip 39, and conductor 41, back to the plug 42. In tracing the above circuit it will of course be understood that the switch 45 has been moved to operative position. As long as cool water passes through the faucet 36 through the floating valve 20 the resistance coil 33 heats the water and it passes through spout 17. As soon as the flow of water is shut off at the faucet 46 the spring 25 moves the floating valve 20 back to normal position and the electrical circuit is immediately broken.

By the above described arrangement of

parts it is apparent that when water ceases to flow from the faucet 46 electrical connection is automatically broken, so that heating of the resistance coils stops. However, if for any reason it be desired to shut off the current to the resistance coils the same may be accomplished by means of switch 45 without disconnecting the plug 42 from socket 43.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim is:

1. As a new article of manufacture, a portable hot water heater comprising an integral body of insulating material having oppositely disposed integral extensions arranged to be detachably secured to the spout of a cold water faucet for self support, said heater comprising a casing of circular cross-section having a chamber arranged for the continuous, uninterrupted passage therethrough of cold water, electrical means including horizontally arranged coils within said chamber for heating the water as it flows through the heater, said means including an electrical circuit arranged to be automatically closed by the continuous flow of water and adapted to be automatically opened by the cessation of water flow, a plug and socket forming part of said electrical circuit, and a manually operable switch included in said circuit for controlling the same independently of said automatic control.

2. As a new article of manufacture, a portable device for heating water comprising a tubular casing of insulating material, said casing being provided with oppositely disposed integral extensions, one of which extensions is upturned and arranged for detachable connection with a faucet and the other of which extensions is downwardly turned for delivery of heated water, and means including electrical heating coils electrically connected within and insulated by said casing for heating water passing through said casing from said upturned and downturned extensions.

SAMUEL S. TORRISI.
